CLAIM

The ornamental design for a finger guard, as shown and described.

DESCRIPTION

FIG. 1 is a rear perspective view of a finger guard, according to an embodiment of the invention.

FIG. 2 is an enlarged front view the finger guard.

FIG. 3 is an enlarged rear view of the finger guard.

FIG. 4 is an enlarged left-side view of the finger guard.

FIG. 5 is an enlarged right-side view of the finger guard.

FIG. 6 is an enlarged top plan view of the finger guard; and, FIG. 7 is an enlarged bottom plan view of the finger guard. The broken lines shown in the drawings are for illustrative purposes only and form no part of the claimed design.
